A CORPORATION OF NEW YORK.

PROPELLED MECHANISM FOR VEHICLES.

Application filed September 26, 1925. Serial No. 53,743.

This invention relates to propelling mechanism for motor-vehicles and more particularly to improvements in the mounting of the motor and in the construction of the propeller shaft and its housing.

The improved propelling mechanism is of that general type in which the axis of rotation of the driving motor is arranged at right angles to the axis of the driven wheels and in which the power is transmitted from the motor to the driving axle through a longitudinal propeller shaft.

Among the objects of the invention are to provide improved propelling mechanism of the above mentioned type in which all of the driving parts from the motor to the driving axle are relieved of all stresses and strains which would otherwise result from the vertical vibration of the rear axle as the wheels pass over irregularities in the road surface; to make it possible to utilize only one universal joint in the propeller shaft and to relieve this joint of all stresses and strains of the character above mentioned; to reduce the unsprung weight of the parts to a minimum; and to provide a simplified and highly efficient propelling mechanism which is rugged in construction and well adapted to withstand heavy duty.

The invention is illustrated in the accompanying drawings in which Fig. 1 is a side elevation, partly in section, of a vehicle bogie having the improved propelling mechanism applied thereto;

Fig. 2 is a plan view of the bogie shown in Fig. 1;

Fig. 3 is a side elevation, partly in section of the bogie shown in Fig. 1, the parts being shown in the position which they assume when the driven wheels are passing over an elevation or irregularity in the roadway;

Fig. 4 is a longitudinal section through the propeller shaft and its housing, the parts being in the same position as shown in Fig. 3, and

Fig. 5 is a vertical transverse section taken on the line 5—5 of Fig. 4.

The improved propelling mechanism is applicable to any motor driven vehicle but it was designed especially for use on the bogies of an eight wheel vehicle having two bogies each provided with four wheels. Therefore, this particular application of the invention has been illustrated in the drawings and will be herein specifically de-

scribed. In practice, the propelling mechanism is associated with both bogies of the vehicle but as it is the same for both the front and rear bogies its application to only one bogie will be described. The bogie itself may be considered as representative of any vehicle because it constitutes in itself a complete driving unit and so far as the present invention is concerned it is immaterial whether this unit is in fact a bogie, a chassis or a complete vehicle.

The frame of the bogie comprises the longitudinal side members 1 and the transverse members 2, 3, 4 and 5. The two transverse members 3 and 4 support between them two longitudinal struts 6 and 7, and the latter support between them a bridge 8 with which there is associated a king pin socket 9. In Fig. 1 there is diagrammatically represented at 10 the body frame of the vehicle, with which there is associated a king pin 11 which engages in the king pin socket 9. This particular manner of mounting the body frame on the bogie is immaterial, so far as the present invention is concerned, but is described merely to show one way in which the bogie may be associated with the body.

The bogie frame is provided with a rear dead axle 12 on the ends of which the rear driven wheels 13 are mounted, the power being transmitted to the driven wheels 13 through the live axle 14.

The bogie is also provided with two front wheels 15 which are mounted at the ends of the front axle 16 to swing about substantially vertical axes 17 and 18. In the particular vehicle for which the present bogie was designed the front wheels 15 are steered automatically by the body, in the case of the rear bogie, and are steered manually in the case of the front bogie. However, as the steering mechanism for the front wheels forms no part of the present invention it has not been completely shown in the drawings.

The front axle 16 is supported upon the two leaf springs 19 and the rear axle 12 is supported upon two leaf springs 20. The two adjacent ends of the springs 19 and 20 at each side of the bogie are connected through an equalizing system comprising the rocker arm 21 and the vertical links 22. Each rocker arm 21 is pivotally supported at the lower end of a bracket 23 rigidly secured to the frame of the bogie.

The source of power in the present instance is an electric motor 24. It is suspended immediately below the rectangular space formed by the transverse member 3, the bridge 8 and the longitudinal struts 6 and 7. The motor is suspended at its center of gravity by a pair of links 25 one of such links being located at each side of the motor. Each of these links is pivotally supported at its upper end on a pin 26 carried by one of the struts 6 and 7. The lower ends of the links 25 receive two horizontally projecting pins or trunnions 27 mounted on the motor. The motor is therefore mounted to oscillate about the horizontal axis of the trunnion pins 27, these pins being so located that the motor is supported substantially at its center of gravity.

The rear axle 12 is provided with an opening to accommodate the propeller shaft and certain parts of its housing. The rear vertical wall of the axle 12 has bolted thereto, adjacent said opening, a differential housing 28 which contains the usual differential gearing connecting the propeller shaft with the driving axle 14. A cup shaped casing 29 is bolted to the front wall of the dead axle 12 immediately adjacent to the opening therein as shown in Fig. 4, this casing being provided at its edge portion with interior threads 29'. The cup shaped casing 29 supports a casting 30 which is screw threaded at its rear end to engage with the threads 29' on the casing 29. The forward end of the casting 30 is provided with a spherical projection 31 which constitutes a part of a hollow universal joint soon to be described. The casting 30 may be locked to the cup shaped casing 29, to prevent rotating relative thereto by means of a key 32 clamped between two lugs 33 on the periphery of the casing 29 and projecting forwardly into one of a series of notches 34 formed on the periphery of the casting 30. By loosening the bolt 35, which clamps the key between the lugs 33, the key may be lifted and the casting 30 may be adjusted axially by turning it and then the key may be replaced in one of the notches 34 and clamped in this position to lock the casting 30 to the casing 29. The purpose of this axial adjustment of the casting 30 will be explained later.

The cup shaped casing 29 and the casting 30 completely enclose a bearing housing 35 in which the rear portion 36 of the propeller shaft may be rotatably mounted in any suitable manner.

The rear end of the motor has rigidly secured thereto a casting 37 terminating at its rear end in a spherical shaped portion 38. The rear edge of the spherical shaped portion 38 has a peripheral flange 39 to which there is bolted an inside spherical shaped projecting plate 40 and a corresponding

outside plate 41. The two plates 40 and 41 are spaced apart a sufficient distance to form between them a spherical shaped recess 42 which receives the spherical shaped projection 31 on the casting 30. The projecting plates 40 and 41 may be formed in two or more parts and bolted together as shown at 43 in Figs. 1, 2 and 3 to facilitate assembling of the parts. The construction just described permits assembling of the parts 75 into a spherical shaped, hollow universal joint which is completely enclosed and constitutes a housing for the universal joint of the propeller shaft.

The universal joint of the propeller shaft 80 comprises one forked member 44 associated with the rear portion 36 of the propeller shaft, and a second forked member 45 which is splined to the armature shaft 46 of the motor. The forks 44 and 45 are interconnected by the usual cross blocks 47 having pins 48 pivotally connected with the forks. The power is transmitted from the armature shaft 46 through the universal joint just described to the rear end of propeller shaft. 90 Neither the armature shaft 46 nor the forked member 45 of the universal joint has any bearing or support in the casting 37. These parts are therefore entirely independent of the casting 37.

The casting 30 is adjusted in the cup shaped casing 29 to bring the center of the spherical universal joint of the housing into coincidence with the center of the universal joint of the propeller shaft. When the casting 30 is thus adjusted in the cup shaped casing 29 the entire housing around the propeller shaft including the casting 30, the spherical universal joint and the casting 37 is moved axially. This is permitted by the links supporting the motor, the latter swinging slightly either forward or backward to accommodate the new adjustment between the casting 30 and the casing 29.

The normal position of the parts is represented in Fig. 1. Now assume that the rear wheels pass over an elevation or irregularity in the road surface such as that diagrammatically represented at 49 in Fig. 3. This will move the rear axle upwardly. The resulting action of the springs and the equalizing system, which is also illustrated in Fig. 3, will cause the rear axle to move not only upwardly but rearwardly, the movement taking place in the arc of a circle. The differential housing 28, together with the casing 29, the casting 30 and the rear portion of the propeller shaft, all being carried by the rear axle 12, will be tilted upwardly to the position shown in Figs. 3 and 4. This causes the parts of the spherical universal joint in the housing to move to the position shown in Figs. 3 and 4, and causes the motor to swing about its hori- 135

5 horizontal supporting axis to the position also shown in these figures. The slight rearward movement of the axle causes the entire motor to swing bodily to the rear, this action being permitted by the links which support the motor. In other words, the axis of the pins 27, which normally lies almost directly below the axis of the pins 26, will move rearwardly from this position as 10 shown in Fig. 3.

15 It will be noted that the entire action described above takes place without imposing any strains or stresses whatsoever upon the universal joint of the propeller shaft or upon the armature shaft of the motor or in fact upon any of the driving parts. Every bit of the force which is necessary to move the parts to the position shown in Figs. 3 and 4 is transmitted through the housing 20 surrounding the propeller shaft and therefore no strains are imposed upon the propeller shaft. The propeller shaft and its universal joint merely follow the movements of the external housing, the shaft and its 25 universal joint being just as free from any stresses and strains in the position shown in Figs. 3 and 4 as in their normal position. The external housing with its universal joint takes up all stresses and strains 30 whether these be stresses of tension or compression, and it also assumes the burden of any vertical or transverse load or any bending strain which might otherwise be imparted to the propeller shaft. It might be said, therefore, that the universal joint and the armature shaft really float at all times within the external housing, this being clearly demonstrated by slight clearances 35 provided between the extremities of the 40 transverse block and the corresponding arms of the fork 44, which clearances are always maintained regardless of the angular position of the parts, thus showing that there is no load imposed by the rear end 45 of the propeller shaft or by the housing upon the forward end of the propeller shaft. All forces which would otherwise tend to produce compressional or tensional 50 stresses in the propeller shaft, or transverse bending strains upon it, are transmitted to the swinging motor through the external housing of the propeller shaft and these 55 stresses are all either borne by the external housing or are reduced or entirely eliminated by the special construction of the housing and the way in which the motor is mounted.

60 If the elevation or obstruction 49 in the roadway be of sufficient height to move the parts to their maximum position, the lower edge of the spherical projection 31 on the casting 30 will engage with the inner end of the spherical recess 42 as clearly shown in Fig. 4 and this will prevent any further 65 movement of the parts. Therefore, even

an unusually large obstruction in the roadway will not result in injury to the propeller shaft because the parts of the external housing will move to their maximum angular relation in which the propeller shaft 70 and its universal joint remain fully relieved of any stresses, and if any breakage occurs it will occur in some part of the external housing which assumes the load. The external housing may be ruggedly constructed 75 and made sufficiently strong to withstand the maximum strains which are likely to be placed upon it in the ordinary course of operation.

80 When the rear wheels move off of the elevation or obstruction 49 and the rear axle returns to its original position the movement of the parts of the housing and the propeller shaft will be the opposite of that described above. During this return movement of the parts of the housing to their original position no strains will be imposed on the propeller shaft or its universal joint and the universal joint will remain free from any load, strains or stresses both during its movement back to its original position and also after it reaches such position.

85 It will be noted that when the rear axle vibrates vertically the universal joint in the propeller shaft and the universal joint in the housing move in an arc of a circle which is convex with respect to the motor. A similar movement of the universal joints takes place in starting, stopping and braking because the drive herein disclosed is of the 90 Hotchkiss type and no torque tube or torsion rods are employed to positively prevent the axle torque from tilting the rear part of the propeller shaft and its housing in such a way as to cause the universal joints to 95 move vertically.

100 It will now be seen that the particular manner of mounting the motor, and the special construction of the propeller shaft and its housing, result in a very simple but efficient propelling and transmission mechanism in which the universal joint in the propeller shaft, as well as the propeller shaft itself are relieved of all stresses which would otherwise be imparted to it by the vertical 105 vibration of the rear axle. The unsprung weight of the parts is reduced to a minimum and the entire mechanism has been found in practice to be generally satisfactory and efficient, especially where the parts are called upon to perform heavy duty as in relatively 110 long trackless vehicles of the type mentioned above having several bogies each of which is provided with four or more wheels.

115 I claim:

120 1. In propelling mechanism for the driven wheels of vehicles comprising an axle with which said wheels are associated, a propeller shaft arranged substantially at right angles to the axle, a motor having a 125

- 1 casing and a drive shaft in substantial alignment with the propeller shaft, a universal joint located in the propeller shaft between the motor drive shaft and the axle, a mounting for the motor permitting bodily axial movement of the motor and oscillation thereof about a horizontal axis, a housing for the propeller shaft interposed between the motor casing and the axle, and a universal joint in said housing substantially concentric with the universal joint in said propeller shaft, said axle being subject to movement that causes said universal joints to move bodily about a center located on that side of the universal joints opposite the motor.
2. Propelling mechanism for the driven wheels of vehicles comprising an axle with which said wheels are associated, a spring suspension for the wheels causing a movement of the axle about an axis to the rear of the axle, a propeller shaft arranged substantially at right angles to the axle, a motor having a casing and a drive shaft in substantial alignment with the propeller shaft, a universal joint located in the propeller shaft between the motor drive shaft and the axle, a mounting for the motor permitting bodily axial movement of the motor and oscillation thereof about a horizontal axis, a housing for the propeller shaft interposed between the motor casing and the axle, and a universal joint in said housing substantially concentric with the universal joint in said propeller shaft.
3. Propelling mechanism for the driven wheels of vehicles comprising an axle operatively connected with said wheels, a motor, a propeller shaft operatively connecting the motor with the axle and provided with a universal joint, a housing for said propeller shaft interposed between the motor and the axle and provided with a universal joint concentric with the universal joint in the propeller shaft that part of the housing and the propeller shaft between the axle and the universal joints being subject to movement that causes the universal joints to move in an arc which is convex with respect to the motor, and a mounting for the motor permitting bodily axial movement of the motor and oscillation thereof about a horizontal axis, all strains except the driving torque which would be imposed on the universal joint in the propeller shaft by said movement of the propeller shaft being minimized by the provision of said housing.
4. Propelling mechanism for the driven wheels of vehicles comprising an axle with which said wheels are associated, a propeller shaft, a motor for driving the propeller shaft, a universal joint located in the propeller shaft, a housing enclosing the propeller shaft and interposed between the axle and the motor, a universal joint in said housing substantially concentric with the universal joint in the propeller shaft, means for mounting the motor to permit bodily axial movement thereof and also oscillation about a horizontal axis, and means for adjusting the effective length of said housing to bring the two universal joints into concentric relation.
5. Propelling mechanism for the driven wheels of vehicles, comprising an axle with which said wheels are associated, a propeller shaft, a motor for driving the propeller shaft, a universal joint in said propeller shaft, a housing enclosing the propeller shaft, a flexible joint in said housing and means for adjusting the position of said flexible joint to bring it into substantially concentric relation with said universal joint.
6. Propelling mechanism for vehicles comprising an axle, a motor pivotally mounted on a movable axis, a propeller shaft with a universal joint therein connecting the axle and motor, that portion of the propeller shaft between the axle and the universal joint being movable about the axle in a plane perpendicular to said axle, a housing about said propeller shaft with a universal joint therein concentric with the aforesaid universal joint.
7. Propelling mechanism for the driven wheels of vehicles comprising in association with said wheels an axle which is bodily movable about an axis to the rear of said axle, a motor axially movable about points from which it is pivotally suspended, a propeller shaft perpendicular to said axle and in alignment with the motor shaft, a universal joint in said propeller shaft and a housing enclosing the propeller shaft having a universal joint therein substantially concentric with the universal joint in the propeller shaft.
8. Propelling mechanism for the driven wheels of vehicles comprising an axle operatively connected with said wheels, a motor, a propeller shaft operatively connecting the motor with the axle and provided with a universal joint, and a housing for said propeller shaft interposed between the motor and the axle and provided with a universal joint concentric with the universal joint in the propeller shaft, that part of the housing and the propeller shaft between the axle and the universal joints being subject to movement that causes the universal joints to move in an arc which is convex with respect to the motor, all strains except the driving torque which would be imposed on the universal joint in the propeller shaft by said movement of the propeller shaft being minimized by the provision of said housing.

In testimony whereof I affix my signature.
OLIVER F. WARHUS.
